TYPE FORM

James Edward Parker, Washington, D. C.

Application August 31, 1933, Serial No. 687,720

6 Claims. (Cl. 101—401.3)

My invention relates to a method and apparatus to be employed in the art of typography. It consists substantially in the method and apparatus, the concepts pertaining thereto, and the construction, combination and arrangement of parts associated in a type form assembly for the practice of my method, as will be more fully set forth hereinafter, represented in the accompanying drawings and finally pointed out in the appended claims.

My invention is applicable to typography wherein type of standard height (i. e., having an overall dimension of approximately 0.9186" between the feet upon which the type rests and the face or part from which the impression is taken) is employed, and especially to typography wherein the type normally rests upon or is supported by its feet, regardless of its height or vertical thickness and of the quantity or kind or characters or the nature of the surface from which or on which the impression is made or taken.

In the class of typography employing type of standard height, it has been customary to depend upon lateral contact and the pressure exerted by clamping means such as quoins, to effectually lock together type units and associated furniture, spacing units, roller bars and other elements of a type form so that no individual part or piece can become disengaged or disengaged; quoins or the equivalent thereof operating to clamp the elements of the form together firmly in such a manner that the entire structure becomes rigid.

In some instances elements of the structure have been provided with a groove on one edge and a rib on the other edge, grooves and ribs engaging to securely interlock the elements so as to prevent movement thereof. This desired rigidity has also been accomplished by providing grooves in lieu of ribs and utilizing locking members such as rods, in lieu of the ribs, to engage adjacent grooves and, thus cooperating, to lock the elements of the form against movement; in this manner providing means additional to the clamping effect between the lines of type and other elements of the form to obtain the customary rigidity.

Heretofore, when lateral contact between elements (with or without the inclusion of additional locking means) has not been employed, it has been customary to arrange type and spacing units in drums or frames having longitudinal type holding bars arranged thereon in pairs forming slots between them, each slot being adapted to receive a line of type and space units. The type and space units, being provided with a pair of notches on each side thereof, are engaged thereby by rails on the longitudinal type holding bars; the rails supporting the type and space units therebetween.

In multiunit type form assemblies, especially those employing type of standard heights, it has been difficult to effectively accomplish complete lateral contact interlocking between all elements so as to assure that each individual piece or unit will be held firmly within the assembly and will not become disengaged or disengaged, except by the employment of special locking means such as described. Providing the equipment with rib and groove features prevents the universal employment of such equipment with standard equipment and restricts the manner in which such special equipment can be utilized in the assembly.

Furthermore, when the elements are properly held by lateral contact or are interlocked forming a rigid structure from which impressions are to be obtained, any irregularities in the height of the face of the type due to uneven wear or use or irregularities of the surface upon which the impression is to be made, will be reflected in the impression obtained in the process of printing or other applications of the assembled elements, requiring replacement of unsatisfactory type or space units or other elements of the assembly, or extensive make-ready on the press or other device employing the assembly before operations can be started. In some instances such preparations do not suffice, for example when varying irregularities exist in impression surfaces.

The same disadvantages obtain in the employment of type and space units in combination with type holding bars the rails of which support the type and space units. This applies especially to the comparatively short type which receives projections from the rails whereby the type is held against radial displacement and to the machines with which such type and space units are used.

Standard type in rigid assembly and special type held by rails of type holding bars retain the assembled units in a fixed relation one to the other in the process of obtaining impression effects. Such special type cannot be set up or used interchangeably with standard type in the fabrication of a type form assembly in the customary manner; the method of handling, retaining and assembling the two styles of type being radically different.

Standard type assemblies, if not clamped or locked together tightly, heretofore have not been dependable for typographical purposes, one reason being that type units can pull or work out of the assembly and spacing elements can assume a position within the plane of the face surface of the type units whereby objectionable impressions will be received therefrom during the process of printing. Furthermore, such standard type assemblies cannot be handled with safety and security due to the possibility of elements dropping out of the form during movement thereof, or becoming disengaged while working on the

assembly such as to make typographical corrections.

Type held by rails and space units used therewith cannot be readily replaced in the assembly, 5 moreover such units are liable to breakage at the thin portion during employment of the assembly such as in the process of printing, thus spoiling or rendering useless, due to imperfect copy, the impressions taken from the type form assembly. 10 Furthermore, type is subject to serious damage during process of printing, should foreign matter be disposed between the type face and the impression surface.

It is to overcome in a practical and readily applicable manner the defects, disadvantages and difficulties referred to above and to utilize to advantage the inherently characteristic tendency of the units to become displaced during the process of printing, and also at the same time to permit the typographical equipment to be handled, if desired, in accordance with established practice with which those at present engaged in the art are familiar, that the present method, means and apparatus have been devised and developed. 25

One of the objects of my invention is to produce at will, even or uneven impression effects with the employment of the same typographical equipment, whether the equipment consist entirely of new or unused units, entirely used or worn units, or a combination of used and unused units, of units not uniformly alike as to standard height, or a combination of used, non-standard and unused units.

Another object of my invention is to provide a method and means whereby a type form assembly may be used to produce desired impression effects on smooth or uneven paper or other surfaces.

Another object of my invention is to provide 40 a method and means whereby character type deficient in vertical height will assume a position within the assembly, due to the inherent tendency of units to work up to the impression surface during the process of printing, so that the desired impression may be obtained therefrom; while at the same time the non-character type units, such as spaces, etc., while capable of vertical movement, will not assume the position within the assembly whereby undesired impressions will 45 be obtained therefrom, due to the inherent tendency mentioned.

Still another object of my invention is to provide a method and means whereby type units co-act 55 with a support to retain the assembled type units in proper relation one with the other to obtain desired impression effects while dispensing with the requirement that the type, spaces and other elements and units constituting or comprising the type form assembly co-operate in holding the type form and units thereof in fixed relation.

A further object of my invention is to provide means whereby a type form assembly may be set up in the customary manner in accordance 65 with usual typographical practice in the process of which means are automatically made available in whole or in part within the assembly for the employment of the method of my invention.

A still further object of my invention is to provide 70 apparatus in the form of typographical equipment which can be used readily in conjunction with standard typographical equipment, elements and units as at present employed in the art and, if desired, which can be made up into a 75 type form assembly wherein only a portion of

the assembly may utilize the method and apparatus of my invention.

Another object of my invention is to provide a method and means whereby a type form assembly may be fabricated wherein the type units are capable of yielding to excessive pressure exerted on the face thereof due to foreign matter being interdisposed between the type face and the impression surface or to irregularities in the impression surface; the type units returning to their proper position for the production of following or subsequent impression effects. 5

Still another object of my invention is to provide means whereby type units and other elements of a type form assembly incorporating 15 units or other elements of non-uniform dimensions which may not be perfectly true in their angles, may be employed to advantage in typography.

A further object of my invention is to provide 20 means whereby a type form assembly which has been set up in the customary manner may be retained ready for immediate production of even or uneven impression effects and may be moved about or otherwise manipulated with minimum 25 danger of spilling or disarranging the type form assembly, and the employment therewith of a guard or intervening member to limit the movement of the units without the member functioning to retain said units in a fixed position with 30 relation one to the other.

Still another object of my invention is to provide a method whereby preferred impression effects may be obtained by preventing elements of a type form assembly from assuming a certain 35 position with relation one to the other instead of obtaining preferred impression effects by holding, locking or otherwise retaining the elements of a type form assembly in a fixed position relative one to the other. 40

Other and further objects of my invention will be understood from the specification hereinafter following by reference to the accompanying drawings in which like reference characters have been used to indicate corresponding parts throughout 45 the several views and in which

Figure 1 illustrates in perspective a typical type form assembly with one end broken away to more clearly disclose the arrangement of parts;

Figure 7 illustrates a plurality of rows of type and spacing elements including guard or intervening members;

Figure 8 illustrates a modification of Fig. 7;

Figure 9 illustrates another form of type, space 65 units and intervening or guard members;

Figure 10 illustrates another position of the ele- ments of Fig. 9;

Figure 11 illustrates the customary or desired position of type and space units, such as Fig. 9, 70 when incorporated in a type form assembly;

Figure 12 illustrates in perspective a typical type unit of my invention;

Figure 13 illustrates a fragmentary portion of 75 a type form assembly containing typical quoins or

form locking units, guard or intervening members in modified form associated therewith; and

5 Figure 14 illustrates a form of thin spacing element employed in the method of my invention, a guard or intervening feature being made a part thereof.

10 In the drawings, I have illustrated apparatus typical of that employing my invention and in the following description I will describe the same as applicable to flat bed typographical equipment, but it is to be understood that modifications thereof may be made to adapt the same to other kinds of typographical equipments and printing machines such as rotating, revolving, and reciprocating machines without departing from the 15 spirit of my invention as defined by the claims appended hereto.

20 While I have disclosed type, space units, spacing equipment, furniture, quoins and other elements of standard dimensions as adapted to incorporate and to utilize the principles of my invention, it is to be noted that type, space units, spacing equipment, furniture, quoins and other elements other than those having standard dimensions may be equally as well adapted and employed 25 so as to incorporate and utilize the principles of my invention.

25 This invention is an improvement over that described in my Patent Number 1,187,085 issued to me June 13, 1916, in which a locking means consisting of rods or middle leads were shown as cooperating with the notches of the type to lock the type against creeping movement, the type and other members of the form cooperating to lock the rods and middle leads against movement, thus all members cooperating to hold the type form in fixed relation and not depending upon the clamping effect between the lines of type as was the usual practice.

40 The non-flexible nature of the structure in the patent referred to (1,187,085) did not permit the objects of the present invention to be achieved by the use thereof, by reason of the fixed relation in which all members of the type form were held.

45 In Fig. 1, I show a typical type form assembly comprising end chase members 20, side chase members 21, the upper portion of which may be detachable as shown at 21a, with furniture units, 22, type, space units, spacing equipment, reglets, 50 quads, and other elements of a type form assembly located therein in rows 23, 24, 25, 26, 27, 28, 29, 30 and 31 and with thin spacers 32 and quoins 33, associated therewith, and with one end chase member, 20, broken away to disclose a guard or 55 intervening member, 34, an open space of rectangular cross section 35, and a recess, 41, in side members 21, the assembly resting on support 36.

60 In Fig. 2 I show a cross-section view of Fig. 1 taken on line 2—2 in which thin spacers 37 and 38, open spaces 39, and additional guard or intervening members 40 not in evidence from inspection of Fig. 1 are indicated. The support 36 is indicated as being comprised of a plurality of sections 36a and 36b.

65 In Fig. 3, I show the end type of a plurality of rows, 23, 25, 28 in close relationship, the type being of the form illustrated and described in Patent 1,187,085 mentioned with the added feature that the open spaces 35 are not grooves 70 forming half of a square but are elongated vertically of the type so that when rows of type 23, 25 and 28 are placed together as shown there are formed between the rows open spaces, 39, of rectangular cross-section, the major axis of 75 the rectangular cross-section being parallel to

the vertical axis of the type; the type resting on support, 36, a portion of which is cut away under row 28 so that this row may be lowered to a level below that of rows 23 and 25.

In Fig. 4, I show a plurality of rows 28, 30, 31 in close relationship, the end type of rows, 28 and 31 being new or unused type while the end type of row 30 is used or worn type, the type resting on support 36 of resilient material, displacements therein by the depression of the high 10 type of rows 28 and 31 having raised the low type of row 30; the open spaces 39 between the rows being maintained.

In Fig. 5, I show the end type of the rows 23, 25 and 28 of Fig. 3 resting on support 36 having 15 an uneven surface so that the type of the several rows are at differing levels, the open spaces 39 between the rows being maintained as in Fig. 4, guard or intervening members 40, substantially 20 the same width as open spaces 39, being disposed in the open spaces 39.

In Fig. 6, I show the end type of the rows 28, 30 and 31 of Fig. 4, resting on support 36, having a smooth surface as in Fig. 1 but without 25 a portion thereof cut away; guard or intervening members 40 being disposed in the open spaces 39.

In Fig. 7, I show the end type of rows 23 and 25 separated by reglet or spacing equipment 26 30 and with spacing equipment 24 or other furniture equipment adjacent to row 25; guard or intervening members 40 being disposed in the open spaces 39 between the type of rows 23 and 25 and the spacing equipment 26 and 24; the type of rows 23 and 25 and the equipment 24 35 resting on support 36.

In Fig. 8, I show the end type of rows 23 and 25 and spacing equipment 26 and 24 of Fig. 7, but with only type of row 23 and the spacing equipment 26 resting on support 36. 40

In Fig. 9, I show the end type of row 23, the spacing equipment 26, the open space 39 and the guard or intervening member 40 of Fig. 7 being modified in form as shown by the curved 45 walls of the groove at 39a and the provision of the circular guard members 40a; the end type of row 23 and spacing equipment 26 being in the same relative position as in Fig. 7.

In Fig. 10, I show the elements of Fig. 9, in the same modified form but in different relative 50 positions, such as the relative positions of the end type of row 25 and spacing equipment 24 of Fig. 8.

In Fig. 11, I show the type and spacing equipment elements of Figs. 9 and 10 in the normal 55 relative position; the guard or intervening member not being disposed therebetween but with the open space 39 provided therefor at 39a.

In Fig. 12, I show a detail of the type such as 60 the end type of the row, 28, of Figs. 3 to 6 inclusive.

In Fig. 13, I show a detail of a quoin or form assembly locking member, 33, with a guard or intervening member 40b disposed in the open 65 space 39b between the sections 33a and 33b comprising quoin 33; the ends of the guard or intervening member 40b being bent to an angle beyond the respective ends of the open space 39b and engaging the two halves of the quoin 33 so 70 as to prevent a detrimental change in the relative position of the two halves of the quoin which would lessen to a detrimental degree the preferred or desired pressure exerted by the quoin on the type form assembly. 75

In Fig. 14, I show a detail of the thin spacers 32, 37 and 38 of Figs. 1 and 2.

From the foregoing, it will be apparent that when a set-up as shown in Fig. 2 is in position 5 within the end members 20 and side members 21 which may constitute a chase and as shown in Fig. 1, by adjusting the side members 21 laterally and by adjusting the end members 20 or quoins 33, the type elements of the assembly may 10 be held with any desired degree of security against lateral movement.

When it is desired to thin-space the elements 15 of the assembly, I have provided thin spacer elements 32, 37 and 38, Fig. 2, the form shown in detail in Fig. 14. These thin spacers 32, 37 and 38 consist of a lead or other thin spacing material having a T head, the thickness of the T head being the same as the thickness of the guard or intervening member, the arms of the 20 T extending out substantially the same distance as the width of the open space 39, it being optional whether the ends of the T head extend beyond the end of the body of the lead or thin spacer, as indicated by the dotted line in 25 Fig. 14. In practice, thin spacers are cut to size according to the purpose they are to serve in a type form assembly.

Referring to Fig. 1, the side members 21 are 30 optionally provided with recesses as 41 of substantially the same depth, vertically, as the guard or intervening members 34 or 40 so that when a set-up of type as shown in Fig. 1 is inserted therein between side members 21, the ends of the guard or intervening members 34 or 40 may be held in 35 position by means of recess 41, as shown in Fig. 1 at the cut away portion of end member 20. To facilitate handling, the upper part of side members 21 may be made removable and replaceable as shown at 21a. Open space 35 of elements of 40 the assembly may serve equally as well as recess 41 to accommodate the end of guard or intervening members 34 or 40 and the head of thin spacers 32, 37 and 38 when desired or required.

When desirable for purposes of composition and 45 arrangement of elements, the length of the guard or intervening members 34 or 40 and of the thin spacers 32, 37 and 38 may be restricted or limited to the length of the line of type or the other elements of the assembly with which they 50 are associated or to any portion of the length, thus not necessarily extending the full length of the line or engaging recesses 41 of side members 21. The lines of type within the assembly may also be set at angles to one another and still 55 utilize the elements of the form associated therewith.

It will be noted that whereas the type unit Fig. 12 has open spaces 35 only at the upper portion thereof, reference to Fig. 2 indicates other elements of the assembly, such as units 22, 24 and 33, have open spaces 35 located at the lower portion as well as the upper portion which permits inversion of space units, reglets, furniture and other spacing elements thus facilitating composition and assembly. Inversion of type units is not regular practice, therefore, open spaces 35 in the lower portion thereof would retard rather than facilitate composition and assembly. Open spaces 35 may be located at the upper portion and lower portion of the ends of the spacing equipments and in the case of furniture of substantially the same crosswise dimensions, open spaces 35 may be located equally as well on the top and on the bottom thereof. Open spaces 35 70 may be located likewise in the sides of slugs cast 75

for typographical purposes in the same manner as in individual type, Fig. 12, as well as in the ends thereof.

When the guard or intervening members, 40, if 5 employed, are in position, individual type although held against lateral movement are free to move vertically a predetermined distance determined by the difference of the dimensions of the open spaces 35 and the guard or intervening members 40 (and of the T head of the thin 10 spacers 32, 37 and 38) used. This distance I have chosen as approximately the height of the face above the shoulder of new type in my practice of the invention as best adapted to produce even copy from a mixture of old and new type. 15

While I have shown in detail the open spaces 35 and 39 as rectangular and the guard or intervening members 40 as square, I do not wish to be limited to this specific structure, since I have used rounded guard or intervening members 40a 20 with the open spaces 35 as substantially semi-ellipses or as arcuate and open spaces 39 as substantially ellipses with the major axis substantially twice the diameter of the guard or intervening members 40 and parallel to the vertical 25 axis of the type Fig. 12 and the minor axis of the ellipses being substantially the same as the diameter of the guard or intervening members 40 lying at right angles to the vertical axis of the type Fig. 12, as indicated in Figs. 9, 10 and 11, the 30 diameter of the guard or intervening members 40 being greater than the maximum horizontal width of open spaces 35 and less than the maximum horizontal width of open space 39, with 35 equally successful results to those obtained with the rectangular open spaces 35 and 39, and the square guard or intervening members 34 and 40.

It is to be understood, however, that other dimensions may be chosen without departing from the spirit of my invention as defined by the 40 scope thereof and pointed out in the claims appended hereto.

Referring to Fig. 1, I have provided supports 36 for type, Fig. 12, and the other elements comprising the assembled set-up. These supports, 45 36, may be either rigid with a smooth surface as indicated in Fig. 6 or an uneven surface as indicated in Fig. 5, or resilient as indicated in Fig. 4, or of several thicknesses of material as indicated in Fig. 3, as few or as many layers of the 50 material being removable or replaceable as and when desired to obtain preferred results. If desired, any of the supports 36 of Figs. 3, 4, 5, 6, 7, and 8 may be used in combination as indicated in the plurality of sections by 36a and 36b 55 of support 36, Fig. 2.

It will be understood that the above description and accompanying drawings comprehend only the general and preferred embodiment of my invention, and familiarity therewith will enable those skilled in the art to understand therefrom that many changes may be made in the form of the embodiment of my invention within the scope of the appended claims without sacrificing any 60 of the advantages of my invention. 65

I will now describe the operation of my invention.

Assuming first the set-up of type shown in Fig. 1 to be entirely of new type but of long and short lines, with the type held against lateral movement 70 by end members 20, quoins 33, if employed, and side members 21, but with each type unit of the assembly free to move vertically an amount predetermined as hereinbefore described.

If it is desired to produce an absolutely even 75

copy effect, support 36 of one or several thicknesses of material with smooth surface is chosen, layers of material being removed from under the short line or any part thereof, such as row 28, 5 Fig. 3, thus lowering the level of type in the short line, row 28, so that when an impression is taken from the type, the pressure of each individual type upon the copy is the same.

If it is desired to produce an uneven copy effect, 10 for example one simulating type-written copy, support 36 is chosen rigid, but having an uneven or irregular surface so that the individual type are moved to various levels as indicated in Fig. 5, with the result that an uneven copy is produced.

15 Assuming next the set-up of type shown in Fig. 1 to be a mixture of high and low type, new and old type, or entirely of old type, with the type free to move vertically an amount predetermined as hereinbefore described.

20 If it is desired to produce an even copy effect, support 36 is chosen, resilient, so that when an impression is taken from the type, the pressure of each individual type upon the copy is equalized and is the same irrespective of the height 25 of the type; high type as in rows 28 and 31, Fig. 4, being depressed in the resilient mat, support 36, produces displacements therein which tend to raise the low type as in row 30, Figure 4.

Due to the inherent tendency of units in a type 30 form assembly to work up to the printing surface, it is evident that the low type in row 30, Fig. 4, will assume a position within the assembly so that the impression effects may be obtained therefrom, without depending upon any displacement 35 in support 36, due to the permitted upward vertical movement allowed the low type. This vertical movement is limited to the extent that type units cannot pull out of the assembly, this feature accomplished by the functioning of the guard or 40 intervening members 40 in restricting the vertical movements of the units making up the assembly, as indicated in Fig. 7, wherein a spacing element, 26, (instead of a low type, as in row 30, Fig. 4) is represented; the tendency of low character type and of spacing units to move vertically 45 within the assembly being the same, as indicated by the position shown of spacing element 26, Fig. 7.

Assuming that copy is to be made on material 50 or on stock which in itself presents or has an uneven surface or which varies irregularly in thickness, with support 36, resilient, and the type being free to move vertically an amount predetermined as hereinbefore described, each individual type unit, Fig. 12 is capable of assuming 55 at each impression a position which will bring the height of the printing surface to the proper level or position from which the impression may be obtained, regardless of the varying thickness 60 of the stock or irregularity in the surface thereof on which the impression is to be made, at the point and at the time of making the impression.

Due to the free vertical movement permitted 65 the type, it is apparent that if the stock upon which the impression is to be made should in any particular instance have foreign matter on the printing surface or elsewhere, such as encountered in the adhesives used on envelopes, which on account of excessive thickness or hardness would 70 tend to damage the face of the type, Fig. 12, should it be locked in a rigid assembly, such possibility of damage can be materially reduced by the employment of support 36, resilient, the elements of the assembly being permitted free vertical 75 movement. The type, subject to abnormal

pressure, would be depressed into the resilient surface during the process of making the impression; the type being returned to its proper position within the assembly for subsequent impression purposes.

If it is desired to produce even or uneven copy effects of the kind previously mentioned, supports 36, if rigid may have a flat or uneven surface as desired, the height of the type faces being relied upon to give even copy, or uneven copy, produced 10 by the artificial irregularities of the surface of support 36.

At the time the character type is permitted free movement in a vertical direction as hereinbefore described, by means of which desired impression 15 effects may be obtained from each type independent of another, the space units between words and the spacing equipment between lines of type and elsewhere in the assembly are likewise capable of free vertical movement in an amount 20 predetermined as hereinbefore described, so that spacing elements will not interfere with the vertical movement of the character type. By reason of the vertical movement of the units being an amount predetermined as hereinbefore described, 25 the spacing elements, being lower than the type units, are prevented from assuming a position within the plane of the printing surface of the character type and are thus prevented from marring the copy as is the case when impressions 30 are obtained therefrom or caused thereby due to their assuming a position in the plane of the printing surface of the character type.

From an examination of Figs. 1 and 2, it will be noted that regular standard typographical equipment, such as regular furniture 22, regular character type units and regular space or quad units represented in row 31 can be readily modified to employ the principles of this invention. Row 27, Figs. 1 and 2, represents regular standard typographical equipment unmodified, as customarily furnished to and employed in the art. It is apparent that such regular standard typographical equipment can be used in conjunction with similar typographical equipment adapted to employ 45 the principles of my invention and vice versa, and also that guard or intervening members, 34 and 40 need not necessarily be employed although provision may be made for their employment, such as open spaces 39, between rows 24 and 25 50 and between other elements of the assembly such as open spaces 39 between furniture 22 and quoins 33.

It will be seen that the elements of the assembly can be locked together in the usual manner by quoins, as 33, and with or without the employment of guard or intervening members 40. It will be noted in Fig. 2 that furniture 22 and reglet 24 may be inverted, these elements indicating a preferred but not essential design of all 60 spacing elements, such as spaces, quads, furniture etc., so that such elements may be handled in the usual manner and not placed in the form in a special position during the composition or fabrication of the assembly. Certain elements, where 65 desired, may also serve as a quad in one line or a space in another line by further continuing the application of the concept wherein open spaces 35 are on the ends as well as on the sides, upper and lower portion, of the units. Certain 70 furniture, such as that having three or a plurality of dimensions substantially the same may be placed in the form in any convenient manner as is usual practice and may be so constructed as to provide, at the same time, means on all sur- 75

faces, such as open spaces 35, and such as four to each side, for the employment of guard or intervening members 40, without effecting the purpose which the furniture is intended to serve.

5 In row 27, Fig. 1, is shown an end space unit as having worked up to the printing surface of the character type, due to defect therein or to other causes commonly met with or encountered in the art. In row 25, Fig. 1, is shown a mid space as 10 having worked up to the printing surface. When such undesired action takes place in an assembly, such raised units can be shoved down. Repetition of such action can be prevented and the disadvantages of the employment of such faulty units 15 or of the existence of causes mentioned can be overcome, without change in or replacement of such unit, or any further adjustment other than pushing down the unit and inserting a guard or intervening member 40, in the rectangular space 20 20 25 39, such as between rows 24 and 25 or between rows 25 and 26; the latter shown in Fig. 2 as having been done. Fig. 2 indicates that this objectionable characteristic cannot be thus overcome in row 27 representing regular standard typographic equipment as no open spaces 35 are supplied therein and thus no open spaces 39 are provided or made available to accommodate guard or intervening members 40.

Reglet 26, is represented as tending to work up 30 to the printing surface, Fig. 2 showing the movement being checked by guard or intervening member 40. Character type, spaces, quads, etc. in row 27 represent regular standard typographical elements of an assembly such as are commonly employed in the art with the end unit indicated as having worked up to the printing surface thus exemplifying disadvantages experienced in the use of regular standard typographical equipment wherein the principles of this invention cannot be enjoyed.

Referring to Fig. 14, I also provide when necessary thin spacers which may be cut to the proper size to be employed in the assembly in the manner desired, such as thin spacers 32, 37 and 38, 45 Fig. 2, which spacers such as 32, may be inserted in an inverted position between rows, such as 29 and 30, Fig. 2, to serve as an additional precaution in preventing type of rows 29 and 30 from breaking off at the thin portion i. e., at open spaces 35 50 of the type, Fig. 12. It is customary in the art to cut any spacing equipment to lengths necessary to meet specific typographical set-up requirements. Therefore, the T head of thin spacers may be cut off if and when desired such as the 55 T head of thin spacer 37, so that the T head only of thin spacers 37 may serve as the guard or intervening member associated with rows 28 and 29 and also for the body of thin spacer 37 thereunder, the body being free to move vertically 60 an amount predetermined as hereinbefore described. Or the T head of thin spacers 32, inverted in the assembly, may serve as the guard or intervening member associated with rows, such as 29 and 30 and for the body only of thin spacers 65 such as 38 without its T head while affording additional protection to the type in the rows with which associated as described above in regard to the possibility of type breaking off at its thin portion such as at open spaces 35 of type Fig. 12. 70 This tendency towards breakage is reduced by the employment of the modified form of open spaces 35a and 39a shown in Figs. 9, 10 and 11. In employing the modified form of open spaces 35a and 39a, the T head of thin spacers, Fig. 75 14, may be modified by rounding the arms of the

T head so that they extend out as previously described but substantially the same distance as the diameter of the modified guard or intervening member 40a, Figs. 9 and 10.

It should be noted that the thin spacers, Fig. 14, when modified by rounding the arms of the T head are not restricted to use with type and spacing equipment only having the modified form of open spaces 35a and 39a shown in Figs. 9, 10 and 11, in order to carry out the spirit and intent of this invention.

In the event that the assembly consists of type and spacing units in drums or frames having longitudinal type holding bars arranged thereon in pairs forming slots between them, each slot 15 being adapted to receive a line of type and space units, rails on the longitudinal type holding bars supporting the type and space units therebetween, it is apparent that support 36 may be inserted in any slot as a strip under the lines of type and 20 space units, the inserted support 36 (instead of the rails on the longitudinal type holding bars) serving to support the type and thus not only overcoming in a practical and readily applicable manner the defects, disadvantages and difficulties referred to herein and providing means for utilizing the method herein described but also coming within the spirit of my invention.

Referring again to Figs. 1 and 2 wherein row 31 is indicated as employing the principles of 30 this invention, it will be noted that four space units are represented towards the center of this row 31, Fig. 1, two units of which are shown as having worked up towards the printing surface, the movements having been effectively checked 35 by reason of guard member 40 being inserted in open space 39 formed in part by row 31, as indicated in Fig. 2. It will be noted also that between quoin 33 and end chase member 20, a guard or intervening member 34 is shown with- 40 in rectangular space 39 therebetween and engaging recess 41. It should be noted that it is not essential that the guard or intervening member 34 extend the full length of rectangular space 39 and engage recess 41 in order to serve its purpose. The same conditions apply to guard or intervening members 40 of the figures shown.

It is to be further understood that the assembly may be mounted directly on the bedplate of a press, the bed plate serving as support 36. 50 Or the bed plate may serve as portion 36b, Fig. 2, and additional support 36a, Fig. 2, of any kind including those described herein, disposed between the assembly and the bed plate, 36b.

Section 36b of support 36 may have an uneven 55 surface or be otherwise adapted to serve as means to prevent undesired horizontal or longitudinal movement of section 36a.

By using furniture, spacing equipment and if desired type and space units with non-parallel 60 latera' sides, the assembly may be mounted in a circular container serving as a chase or galley from which impressions may be obtained from typographical machines operating on several principles, such as the rotary principle. 65

Quoins, 33, may be employed to lock the elements of the assembly in a rigid structure in the customary manner or merely to cause a lesser degree of lateral contact between the elements of the assembly and when the proper or desired 70 degree of contact has been obtained, guard or intervening member 40b, Fig. 13, may serve to retain this preferred or predetermined degree of contact by merely bending member 40b at its ends as shown in Figs. 2 and 13 whereby it is evi- 75

dent that quoins, such as 33, cannot loosen beyond a predetermined amount due to vibrations or other causes during employment of the assembly in the art.

5. Shifting a type form assembly due to handling involves difficulties, such as indicated in Fig. 8 wherein a loosely bound assembly has partially slipped off of its support 36, which movement except for the guard members 40 functioning as indicated would have permitted a vertical downward movement of row 25 and spacing element 24 to the extent of their dropping out of the assembly thus permitting disarrangement of the other elements of the assembly and it is manifest therefore that the assembly, bound loosely, may be lifted or moved about with safety and without support, 36, of necessity being associated therewith, although the elements are not held in a fixed relation one to the other as is the usual practice, further explanation being considered unnecessary.

A further advantage is manifest in closely set-up assemblies represented in Figs. 3 to 6 inclusive and by rows 30 and 31 of Fig. 1 when it is desired to remove any portion of type or equipment from any row, and with guard or intervening members 40 functioning preventing type or equipment of adjacent rows from becoming disarranged and spilling, or from interfering with the replacement of type or equipment in any row, in that the exchange of units and other changes required may be easily effected and the type units, spaces and other elements of the assembly quickly and easily brought into lateral contact, one with another, without each individual unit being necessarily first properly seated or first placed in the normal position, one to the other, at which each element of the assembly must be placed if the assembly is fabricated or held readily for use as a rigid structure, the elements held in a fixed relation one to the other as is the usual practice.

While I have described my invention in certain of its preferred embodiments, I desire that it be understood that modifications may be made and that no limitations upon my invention are intended other than are imposed by the scope of the appended claims.

Having thus described my invention, what I claim is:

50. 1. A type form assembly, comprising a plurality of rows of type units each type unit being provided with opposed recesses on opposite sides thereof intermediate between the ends of said units, the recesses in the type units registering to form a continuous passage between adjacent rows and intervening rod-like members therebetween lying within the recesses in said units, said rod-like members having dimensions smaller than said passage, the type units of the assembly being movable longitudinally of said units a distance less than the difference in the face height and the shoulder height of the type units.

65. 2. A type form assembly including a plurality of rows of type units each type unit being provided with opposed recesses on opposite sides thereof intermediate between the ends of said units, the recesses in the type units registering to form a continuous passage between adjacent rows and intervening members between said rows lying partly within the recesses of one row and partly within the recesses of the adjacent row, said intervening members being of such dimen-

sions as to substantially fill said recesses as to depth but being incapable of filling said recesses for their entire length along the longitudinal axis of said units, by an amount less than the height of the type face above the type shoulder, 5 and a yieldable support for the feet of said type so that type of slightly varying lengths are slideable longitudinally to give a substantially uniform printing surface.

3. A type form assembly including a plurality 10 of rows of type units each type unit being provided with opposed recesses on opposite sides thereof intermediate between the ends of said units, the recesses in the type units registering to form a continuous passage between adjacent 15 rows and intervening members between said rows lying partly within the recesses of one row and partly within the recesses of the adjacent row, said intervening members being of such dimensions as to substantially fill said recesses as to 20 depth but being incapable of filling said recesses for their entire length along the longitudinal axis of said units, by an amount less than the height of the type face above the type shoulder, 25 and a slightly uneven support for the feet of said type whereby an impression resembling typed copy as to density may be obtained.

4. A type form assembly embodying a chase having oppositely recessed sides, a plurality of rows of type units within said chase each type 30 unit being provided with opposed recesses on opposite sides thereof intermediate between the ends of said units, the recesses in the type units registering to form a continuous passage between adjacent rows and a plurality of rods extending 35 across the chase, said rods being of such dimensions that the ends thereof rest within the recesses in the sides of said chase while that portion of the rods intermediate the ends thereof rest within and partially fill the recesses in said type 40 units but fail to fill said recesses in a direction longitudinal of the type unit by an amount less than the height of the face of a relatively new type unit above the shoulder of any type unit.

5. A type form assembly, comprising a plurality 45 of rows of type units, said units being provided with opposed recesses on opposite sides thereof intermediate between the ends of said units, in combination with a plurality of intervening rod-like members therebetween lying 50 within the recesses in said units, said rod-like members having dimensions smaller than the passage formed by said recesses, the type units of the assembly being movable longitudinally within the assembly a distance less than the 55 height of the face of the type of said units above the shoulders, the recesses and rods being so shaped that relative movement of the type units causes an increasing lateral pressure between adjacent type units in adjacent lines of type. 60

6. A type form assembly comprising a pair of rows of type units, each type unit being provided with opposed recesses on opposite sides thereof intermediate between the ends of said unit, the recesses in the type units registering to 65 form a continuous closed channel between two rows thereof and an elongated member in the channel, said member being smaller in the dimension longitudinal of the type units by an amount less than the height of the type faces 70 of the character type above the type shoulders.

JAMES EDWARD PARKER.
